UNITED STATES PATENT OFFICE.

THURE E. DAHL, OF NEW YORK, N. Y.

DESIGN FOR AN ARM FOR ELECTRIC FIXTURES.

60,898.

Specification for Design.

Patented Apr. 25, 1922.

Application filed May 31, 1921. Serial No. 473,923. Term of patent 3½ years.

To all whom it may concern:

Be it known that I, THURE E. DAHL, a subject of the King of Sweden, residing at New York, in the county of New York and State of New York, in the United States of America, have invented a new, original, and ornamental Design for an Arm for Electric Fixtures, of which the following is a

specification, reference being had to the accompanying drawing, forming part thereof.

The figure is a perspective view of an arm for electric fixtures, showing my new design.

I claim:

The ornamental design for an arm for electric fixtures, as shown.

THURE E. DAHL.
